(Cl. D81—10)

To all whom it may concern:

Be it known we, Henri Desguin and Nestor Sauvage, citizens of Belgium, residing respectively at 24 Place Simonis, Koekelberg (Belgium), and 3 rue des Combattants, Berchem-Ste.-Agathe (Belgium), have invented a new, original, and ornamental Design for a Gas Table Stove, of which the following is a specification, reference being had to the accompanying drawing, forming a part hereof.

Fig. 1 is a perspective view of a gas table stove embodying our new design, with the cover closed. The back is plain and the side, not shown, is like the side shown.

Fig. 2 is a view similar to Fig. 1, but showing the cover of the table stove in open position.

We claim:

The ornamental design for a gas table stove, as shown and described.

HENRI DESGUIN.
NESTOR SAUVAGE.
